UNITED STATES PATENT OFFICE.

SAMUEL BERGSTEIN, OF MIDDLETOWN, OHIO, ASSIGNOR TO THE INTERSTATE FOLDING BOX COMPANY, OF MIDDLETOWN, OHIO.

PAPER BOX AND THE LIKE.

Application filed January 26, 1925. Serial No. 4,796.

This invention relates to paper boxes, having particular reference to boxes adapted to be adjusted to display their contents.

Boxes of this character are now being used in great quantities, and the conditions governing their production, distribution, and use are becoming increasingly important.

To enable the box manufacturer to compete in the sale of his product, the boxes must be adapted for low cost production,—with the minimum in labor cost and in waste of paper stock from which the box blanks are cut.

To this end my improved box is designed to adapt the blanks from which the boxes are made to be cut with little or no waste; the boxes are adapted to be cheaply made by hand, also on large production orders by automatic or semi-automatic machinery. The improved box is also convenient to set-up to receive its contents and to be adjusted to display the same, as on a counter or table.

In the accompanying drawings:

Figs. 1 and 2 illustrate the stock blanks from which the boxes are made in two forms;

Fig. 3 is a side view of the box closed;

Fig. 4 is a sectional view of the box set up;

Fig. 5 is an end view of the box set up;

Figs. 6 and 7 illustrate modifications of construction;

Fig. 8 is a detail view of the bottom of the box showing the arrangement of the parts which form the pedestal for supporting the box in display position.

The two forms of blanks illustrated in Figs. 1 and 2 are substantially identical, except that one blank is for a box adapted to be set-up for display endwise, and the other for a box to be set-up side-wise. Thus a detailed description of but one blank will be sufficient for an understanding of the novel features of construction.

The form shown in all the figures of the drawing, except Fig. 2, is for a box to be set-up endwise,—the blank being shown in duplicate to illustrate the manner of cutting the stock to prevent waste of material.

As here shown, the box blank comprises a bottom portion 1, opposite side portions 2, ornamental side border or flap portions 3, a lid composed of portions 4, 5 and 6, an end composed of portions 7, 8, 9 and 10, an opposite end composed of portions 11, 12 and 13, and

a pedestal composed of portions 14, 15 and 16. To effect interlocking of the several parts one with another as the box is set up, part 9 is provided with an irregular shaped slot or keeper 17, and 10 with an insert flap 18 adapted to interlock with slot 17; part 12 with a slot 19, and part 11 with an insert flap 21 adapted to interlock with slot 19,—the flap 21 being adapted to be folded to permit the flap to enter slot 19, and to be then opened to retain the flap in the slot; part 14 is provided with a tongue 16 having opposite tabs 16^a with clearance notches 16^b between the tabs and part 14, the tabs 16^a being adapted to coact with opposite slots 22 in the bottom of the box, as best shown in Fig. 8. It will be observed that parts 14 and 15 are formed into an inverted triangular-shaped base or pedestal, best shown in Fig. 4, which acts to support the box at a suitable angle to display its contents. To stiffen and support the triangular base, tabs 16^a are adapted to be inserted into opposite slots 22 with notches 16^b engaging the outer edges of the slots, as illustrated in Fig. 8. It will be observed that slots 22 are inclined inwardly, one toward the other toward the rear of the box, and that each slot has an outwardly inclined terminal 22^a which acts to interlock with the notches 16^b when the pedestal is formed. When the box is closed normally, that is to say, with the pedestal flap 14—15 extended parallel with the bottom of the box, as illustrated in Fig. 3, and in the dotted outline of the flap in Fig. 8, tabs 16^a will be in engagement with slots 22 at a point farthest removed from the rear end of the box. Thus when it is desirable to adjust the box for displaying its contents, the adjustable part 14—15 is drawn outwardly until it is given the triangular shape illustrated in Fig. 4 in which relation tabs 16^a and notches 16^b will be in engaged relation with terminal slots 22^a, this being effected as a result of the inward inclination of slots 22 which act to compress or buckle part 14 more or less as parts 14—15 are adjusted and notches 16^b slide along in slots 22, with the result that an interlocking relation between 16^a—16^b and 22^a will be effected upon part 14 being restored to its normal or flat shape when slots 16^b and 22^b are brought into register.

Part 15, as here shown, is provided with a

tab 23 which acts to stiffen the triangular base 14-15 rearwardly and thus to maintain the same more or less accurately in normal relation.

5 Figs. 6 and 7 illustrate modifications of construction of the box set up sidewise for display,—the modifications relating to a different arrangement for interlocking the ends of the box, as shown in Fig. 6, and in a double pedestal arrangement, as shown in Fig. 7. The modified end construction represents common practice, and the double pedestal arrangement is substantially the same as that described in connection with 10 the single pedestal box.

15 From the detailed description and the drawings my invention will be easily understood. I claim:

1. A paper folding box including in combination with bottom and side portions, said bottom portion having opposite slots inclined one toward the other rearwardly of the box, end portions extended from said side portions, a flap extended from the bottom portion intermediate the end parts, said parts being adapted to be folded one relative to another to form an end of the box, and a part arranged intermediate said end parts in the plane of said bottom part and having

opposite tabs and notches acting to engage the slots in said bottom, said intermediate part being adapted to be shaped into a pedestal with said tabs and notches coacting slidably with said slots whereby to support the pedestal as the same is moved in position 35 under the box.

2. A paper folding box including in combination with bottom and side portions, said bottom portion having opposite slots inclined one toward the other rearwardly of the box, end portions extended from said side portions, a flap extended from the bottom portion intermediate the end parts, said parts being adapted to be folded one relative to another to form an end of the box, 40 and a part arranged intermediate said end parts in the plane of said bottom part and having opposite tabs and notches acting to engage the slots in said bottom, said intermediate part being adapted to be shaped 45 into a pedestal with said tabs and notches acting to engage and slide rearwardly in said slots and interlock with the bottom as the pedestal is adjusted under the box.

50 In testimony whereof, I affix my signature.

SAMUEL BERGSTEIN.
